UNITED STATES PATENT OFFICE.

JULIAN G. GOODHUE AND HUBERT K. HENRY, OF CHICAGO, ILLINOIS, ASSIGNORS, BY DIRECT AND MESNE ASSIGNMENTS, TO ABSOLUTE DISINFECTING COMPANY, A CORPORATION OF ILLINOIS.

VAPORIZER FOR DISINFECTANTS.

No. 876,904.

Specification of Letters Patent.

Patented Jan. 14, 1908.

Application filed April 19, 1906. Serial No. 312,530.

To all whom it may concern:

Be it known that we, JULIAN G. GOODHUE and HUBERT K. HENRY, of Chicago, Cook county, Illinois, citizens of the United States, have invented certain new and useful Improvements in Vaporizers for Disinfectants, of which the following is a full and correct specification, reference being had to the hereto accompanying drawings, forming a part hereof, and in which—

Figure 1 shows a vertical longitudinal central section of nearly every part of our device in working condition; Fig. 2 shows a transverse section of the tank in the upper part of our structure the same being taken on the cutting-plane 1, 1 of Fig. 1, a part of the said tank being shown broken away; Fig. 3 shows the flanged bottom of the device, a part of the same being shown broken away. Fig. 4 shows a plan view of the parts *j*, *k*, *l*. Fig. 5 shows a central vertical longitudinal section of the part *l* and the lower part of the shell *j*. Fig. 6 shows a siphon in longitudinal central section provided with a vent and plug therein and a wick in the bore of said siphon. Fig. 7 shows a plain siphon in central longitudinal section.

Like reference letters denote like parts throughout.

The object of our invention is to produce a device of the character named which shall be easily controlled and be as near as may be free from the defects of similar devices now in use.

To attain said desirable ends we construct our said new device in, substantially, the following manner, namely; We provide a cylindrical shell or holder *a* proportioned substantially as shown and provide it with a flanged bottom support or ring *n* on which rests rotatably a bottom *p* provided with a flange *p*⁰ and diametrically opposite holes *p'* and *p*² and a notch *q*² in said flange to receive the locking-bolt *r*. Onto said bottom is placed a flanged disk *l* and on it a sheet-metal cylinder *j*, open at both ends, and its sides covered with and supporting a wicking *k* and holding within a vessel or tank *i* provided with a cover having a central short stud or leg *i*² and holes *i'*. The shell *j* may have notches *m* in its lower edge for the purpose of passing the fluid from *i* to the wicking *k* more freely. Said holder *i* is filled with a perfuming liquid which is absorbed into said wicking from which it then evaporates and

passes through the numerous holes *o* in the shell or jacket *a* to perfume the air of the apartment. The tank *i* is filled with the perfuming liquid which is held by atmospheric pressure, or hermetically in said reservoir from which it is let out little by little through holes *i'* through which air is let in whenever an air space is made below the plate containing the holes *i'* so that a little air at a time may enter the tank *i* through said holes *i'*. As soon as enough liquid runs out into the sealing-pan *l* to raise the surface level of the liquid up to the said holes *i'* the outflow from the tank *i* ceases until, again, enough liquid has been evaporated from the vessel *l* to again admit air through the holes *i'* into said reservoir, and so on constantly.

The tank *b* is closed at both ends and contains a disinfecting liquid which is also held in place by atmospheric pressure; the air-entrance being through the internal side-chamber *c* at the lower and open end of its downward extension *c'* leaving a space *f* between the end of the part *c'* and the bottom of the tank *b*. Said tank *b* is filled by laying *75* on its side with the chamber *c* uppermost. When the tank is erected the liquid is air-locked and can only come up through the part *c'* into *c* by allowing air to enter in under the bottom edge of *c'*. This is accomplished *85* by means of the siphon *d* which exhausts the liquid until its surface is below the lower end of *c'* and thereby opens a way for air to get on the inside of its wall and thus allow some of the liquid from the tank *b* to fill up the *90* lower part *c'* far enough to check the entrance of more air, and so on continuously. In said case the lowering of the liquid-surface in the chamber *c* is effected by means of a siphon *d* which empties into a pipe *e* either through the *95* bore of said siphon or by means of a wicking *r*^x which fills the bore of said siphon to the desired degree so as to be aided by atmospheric pressure, or, where desirable, the atmospheric pressure may be dispensed with *100* by removing a cork *d*² from the bend of the siphon so that said wicking may act by means of capillary attraction only. The fragmentary pipe *e* is a part of the pipe *e'*, which is, normally, or preferably, diametrically, opposite the stem *g*. Said pipe *e* is here shown brought around ninety degrees from said position so as to show it in connection with the siphon *d* in a side view so as to more clearly show the construction of said parts. *110*

The relative positions of said parts *e* and *g* is, however, unimportant in any other way except as a matter of convenience because the bottom *p* may be turned to any position. 5 The locking-stem *g* passes through a hole *p'* and it is provided with a hole through which a pad-lock *h* is held, whereby said parts are locked to place. The object of the arrangement of the holes *p'* and *p*², and the rotatable 10 condition of the part *p* is to enable placing the pipe *e* so that it may drop its liquid into either the bowl or the urinal, as the case may be.

The drawing shows that the upper end or 15 head of the tank *b* projects beyond its sides, forming a flange, which projects from its sides and wherewith said tank is supported on the top edge of the holder *a* on which it may turn, axially, and the flanged part *p* is 20 axially coincident with the tank *b* and rotatable on the same axial line, therefore said parts may be placed so that the discharge pipe *e'* may correspond to any desired radial direction. The parts *q* are lugs on the holder 25 *a* through which nails or screws may pass for fastening the device to a vertical support.

What we claim is:

1. In a disinfecting apparatus the combination with a tank-holder and a tank in said 30 holder provided with an interior side-chamber, open at its lower end and hermetically sealing said tank, of a siphon provided with a capillary core and a closable vent, in said chamber and a discharge-pipe under the 35 siphon-discharge and within said holder substantially as specified.

2. In a disinfecting apparatus the combination with a cylindrical and foraminated

tank-holder and an end-closed tank in its upper portion provided with a side-opening 40 closed by an inner chamber extending downward below said opening, and having its lower end open, of a siphon in said chamber and a discharge-pipe under the siphon discharge and within said holder substantially as specified. 45

3. In a disinfecting apparatus the combination with a foraminated tank-holder, of superimposed tanks therein, the upper tank provided with an interior open-bottomed side-chamber hermetically sealing its contents, said chamber provided with a siphon, and a discharge-pipe under the discharge of 50 said siphon and in said tank-holder, the lower of said tanks hermetically sealed by a sealing-pan, wicking in said pan to evaporate its liquid and to pass the vapor thereof through said foraminations substantially as specified. 55

4. In a disinfecting apparatus the combination with a foraminated tank-holder, of superimposed tanks therein, the upper tank axially revoluble and having an interior open-bottomed side-chamber and provided with a siphon, and a discharge-tube to the discharge of said siphon, said tube circumferentially adjustable in said holder, said lower tank hermetically sealed with an evaporating-pan, adapted to form a liquid seal and containing a circular wicking substantially 60 as specified. 65

JULIAN G. GOODHUE.
HUBERT K. HENRY.
